CHEST OF DRAWERS

Wesley A. Rundell, Louisville, Ky.

Application May 6, 1952, Serial No. 19,604

Term of patent 14 years

(Cl. D33—13)

To all whom it may concern:

Be it known that I, Wesley A. Rundell, a citizen of the United States of America and a resident of Louisville, in the county of Jefferson, Commonwealth of Kentucky, have invented a new, original, and ornamental Design for a Chest of Drawers, of which the following is a specification, reference being had to the accompanying drawing, forming a part hereof.

Figures 2, 3 and 4 are sectional views along lines 2—2, 3—3 and 4—4 respectively of Figure 1, these views showing the face contour at the points indicated.

I claim:

The ornamental design for chest of drawers, as shown.

WESLEY A. RUNDELL.
